(57) **CLAIM**

The ornamental design for an electronic atomizing device assembly as shown and described.

DESCRIPTION

FIG. 1 is a front, top, and right side perspective view of the electronic atomizing device assembly, with second component removed from the assembly for clarity of disclosure, according to a first embodiment of our design;

FIG. 2 is a rear, bottom, and left side perspective view of FIG. 1;

FIG. 3 is a front elevational view of FIG. 1;

FIG. 4 is a rear elevational view of FIG. 1;

FIG. 5 is a left side elevational view of FIG. 1;

FIG. 6 is a right side elevational view of FIG. 1;

FIG. 7 is a top plan view of FIG. 1;

FIG. 8 is a bottom plan view of FIG. 1;

FIG. 9 is a front, top, and right side perspective view of the electronic atomizing device assembly, with first component removed from the assembly for clarity of disclosure, according to a first embodiment of our design;

FIG. 10 is a rear, bottom, and left side perspective view of FIG. 9;

FIG. 11 is a front elevational view of FIG. 9;

FIG. 12 is a rear elevational view of FIG. 9;

FIG. 13 is a left side elevational view of FIG. 9;

FIG. 14 is a right side elevational view of FIG. 9;

FIG. 15 is a top plan view of FIG. 9;

FIG. 16 is a bottom plan view of FIG. 9;

FIG. 17 is an enlarged view of area 17 circumscribed in FIG. 13;

(Continued)

FIG. 18 is an enlarged view of area 18 circumscribed in FIG. 14;
 FIG. 19 is a front, top, and right side perspective view of the electronic atomizing device assembly, shown fully assembled by the first component and second component, according to a first embodiment of our design;
 FIG. 20 is a rear, bottom, and left side perspective view of FIG. 19;
 FIG. 21 is a front elevational view of FIG. 19;
 FIG. 22 is a rear elevational view of FIG. 19;
 FIG. 23 is a left side elevational view of FIG. 19;
 FIG. 24 is a right side elevational view of FIG. 19;
 FIG. 25 is a top plan view of FIG. 19;
 FIG. 26 is a bottom plan view of FIG. 19;
 FIG. 27 is an enlarged view of area 27 circumscribed in FIG. 23;
 FIG. 28 is an enlarged view of area 28 circumscribed in FIG. 24;
 FIG. 29 is a front, top, and right side perspective view of the electronic atomizing device assembly, with second component removed from the assembly for clarity of disclosure, according to a second embodiment of our design;
 FIG. 30 is a rear, bottom, and left side perspective view of FIG. 29;
 FIG. 31 is a front elevational view of FIG. 29;
 FIG. 32 is a rear elevational view of FIG. 29;
 FIG. 33 is a left side elevational view of FIG. 29;
 FIG. 34 is a right side elevational view of FIG. 29;
 FIG. 35 is a top plan view of FIG. 29;
 FIG. 36 is a bottom plan view of FIG. 29;
 FIG. 37 is a front, top, and right side perspective view of the electronic atomizing device assembly, with first component removed from the assembly for clarity of disclosure, according to a second embodiment of our design;
 FIG. 38 is a rear, bottom, and left side perspective view of FIG. 37;
 FIG. 39 is a front elevational view of FIG. 37;
 FIG. 40 is a rear elevational view of FIG. 37;
 FIG. 41 is a left side elevational view of FIG. 37;
 FIG. 42 is a right side elevational view of FIG. 37;
 FIG. 43 is a top plan view of FIG. 37;
 FIG. 44 is a bottom plan view of FIG. 37;
 FIG. 45 is an enlarged view of area 45 circumscribed in FIG. 41;
 FIG. 46 is an enlarged view of area 46 circumscribed in FIG. 42;
 FIG. 47 is a front, top, and right side perspective view of the electronic atomizing device assembly, shown fully assembled by the first component and second component, according to a second embodiment of our design;
 FIG. 48 is a rear, bottom, and left side perspective view of FIG. 47;
 FIG. 49 is a front elevational view of FIG. 47;
 FIG. 50 is a rear elevational view of FIG. 47;
 FIG. 51 is a left side elevational view of FIG. 47;
 FIG. 52 is a right side elevational view of FIG. 47;
 FIG. 53 is a top plan view of FIG. 47;

FIG. 54 is a bottom plan view of FIG. 47;
 FIG. 55 is an enlarged view of area 55 circumscribed in FIG. 51; and,
 FIG. 56 is an enlarged view of area 56 circumscribed in FIG. 52.

The broken lines consisting of evenly spaced dash lines in the drawings depict portions of the electronic atomizing device assembly that form no part of the claimed design. The broken lines consisting of short and long dash lines encircling the enlarged detail views are for annotative purposes that form no part of the claimed design. The oblique shade lines in the drawings show transparency.
